UNITED STATES PATENT OFFICE

LAURENCE E. BLOOD, OF BOSTON, MASSACHUSETTS, ASSIGNOR TO S. A. WOODS MACHINE COMPANY, OF BOSTON, MASSACHUSETTS, A CORPORATION OF MASSACHUSETTS

TRAVELING-BED FEED FOR WOOD PLANERS

Application filed June 20, 1929. Serial No. 372,329.

This invention relates to a traveling bed work-feeding device, adaptable particularly for use on wood-planing machines wherein the traveling bed forms an element of a feeding couple gripping the work and feeding it forward frictionally to the planing knives. I provide an efficient, sturdy and inexpensive construction having, furthermore, certain advantages which will appear as the description proceeds.

My invention will be well understood by reference to the following description, taken in connection with the accompanying drawings of an illustrative embodiment of the device, wherein:

Fig. 1 is a fragmentary, side elevation of a wood-planing machine illustrating the organization therewith of a feeding mechanism illustrative of my invention;

Fig. 2 is a longitudinal section, showing the feeding mechanism in side elevation;

Fig. 3 is a section on line 3—3 of Fig. 2; and

Fig. 4 is a fragmentary plan view of the traveling bed proper.

Referring to Fig. 1, I have there shown a portion of a wood-planing machine having the top head 5, beneath which the pieces of wood are advanced in endless succession by the feed mechanism shown at the right, one piece of work pushing another beneath the cutting knives. The feeding mechanism embodies the traveling bed 7, to be described in detail hereafter, against the upper run of which the work is pressed by means of suitable cooperating pressure means, such as the driven rolls 9, mounted to swing about the center 11, and pressed toward the bed by the springs 13. The construction of these cooperating pressing members herein shown by way of example is not in itself novel, and does not require extended description. As will appear, the top of the bed beneath these rolls is essentially flat or uniform and the work is fed by being gripped between the same and the rolls 9 and projected forward by such frictional engagement.

Referring to Fig. 4, to form the bed I may utilize bar-like links 15, longitudinally disposed and arranged in staggered relation,

and linked together by transverse pins 17 to form one or more endless chains (see Fig. 2). Herein the pins 17 are shown extending across the entire width of the feeding bed to form a single chain and, in any case, the effect is as of the single chain, the parts being operated substantially as a unit by the driving sprockets. The exposed faces of the links form a substantially uniform bed without major projections, such as the feed lugs utilized on some types of conveyors to push forward the work, and on this bed the work is pressed by the rolls 9.

The pins 17 may also receive rollers 19, interspersed with the links in longitudinal series, three rows of said rollers being herein shown. As best seen in Fig. 3, the rollers 19 and links 15 are of such size that the former are received wholly below the exposed faces of the latter and form no part of the work-engaging face of the chain. However, the rollers are herein shown as projecting inwardly beyond the inner faces of the links, so that they may run on a suitable support 21 underlying the upper run of the chain, this support being herein shown as a table provided with openings 23, but of course continuous like a rail under each series of rollers 19 utilized for supporting purposes. The support and the rolls may be suitably shaped cooperatively to support the traveling bed against lateral movement, and I have herein shown the support as provided with longitudinal flanges 25 engaging the sides of the central series of rollers.

A driven sprocket 27 on shaft 29 at the forward end of the chain and an idle sprocket 31 on shaft 33 at the rear end of the chain are utilized for supporting and driving the same, and they mesh with certain series of the rollers as shown in Fig. 2, as for instance the two lateral sets of Fig. 3.

The rolling support provided by rollers 19 permits utilizing the device and the feeding mechanism in installations in which great pressure is exercised, as by means of the rolls 9, and as is required in the case of a planer feed. The construction is obviously rugged, simple and cheap. While the exposed surface of the traveling bed 7 is substantially

uniform, yet spaces are provided between the links 15 facilitating the discharge of dirt and small particles, which, in the example of the invention shown, may gravitate through the 5 openings 23. When the feed is utilized on a planer in the more restricted technical sense of the word, that is, in a planing machine feeding relatively large and heavy boards, the honeycombed surface serves effectively to 10 grip the stock, without, however, objectionably marring it. It should be understood, however, that the invention is useful and adaptable to planers in the more general sense of the word, that is, any machine in 15 which wood is cut by planing knives and in which the feed projects the work forward to a relatively remote point of operation of such knives.

I am aware that the invention may be embodied in other specific forms without departing from the spirit or essential attributes thereof, and I therefore desire the present embodiment to be considered in all respects as illustrative and not restrictive; reference 25 being had to the appended claims rather than to the foregoing description to indicate the scope of the invention.

I claim:

1. In a wood-planing machine the feed 30 mechanism for advancing the work to a remote point of operation of planing knives, comprising the travelling bed consisting of a plurality of bar-like links longitudinally disposed in staggered relation, hinge pins joining said links in an endless chain to provide a substantially uniform but perforate supporting surface, rollers on said pins interspersed with said links and disposed inwardly of the outer face thereof but projecting beneath the 35 same, a support for the upper run of the chain on which at least certain of said rollers travel, pressure means for confining the work to said run, sprockets engaging at least certain of the rollers and means for driving the 40 chain thereby.

2. In a wood-planing machine the feed mechanism for advancing work to a remote point of operation of planing knives, comprising the travelling bed consisting of a 50 multiplicity of bar-like links longitudinally disposed in staggered relation, transverse hinge pins joining said links in an endless chain, rollers turning on said pins but received beneath the exposed faces of the links, 55 a support for the upper run of the chain on which at least certain of said rollers travel, cooperating pressure means for engaging the work between the same and the exposed faces of said links in said upper run and sprockets 60 for supporting and driving the chain meshing with at least certain of said rollers.

3. A travelling feed bed comprising an 65 endless chain consisting of a multiplicity of staggered longitudinally extending bar-like links and transverse hinge pins connecting

the same, rollers turning on the pins, said rollers received inwardly of the outer face of the links and projecting inwardly beyond them, a support for the upper run of the chain on which at least certain of said rollers 70 travel, and cooperating pressure means opposing said run to confine work against the exposed faces of said links for frictional advance thereby, and sprockets for supporting and driving the chain meshing with at least 75 certain of said rollers.

4. A travelling feed bed comprising an endless chain consisting of a multiplicity of staggered longitudinally extending bar-like links and transverse hinge pins connecting 80 the same, rollers turning on the pins, said rollers received inwardly of the outer face of the links and projecting inwardly beyond them, means underriding said rollers to support the upper run of the chain and having provision cooperating with said rollers to prevent lateral movement thereof, and cooperating pressure means opposing said run to confine work against the exposed faces of said 85 links for frictional advance thereby, and sprockets for supporting and driving the chain meshing with at least certain of said rollers.

In testimony whereof, I have signed my name to this specification.
